POWER GARMENT AND LAUNDRY PRESSING MACHINE.

Application filed March 13, 1923. Serial No. 624,834.

To all whom it may concern:

Be it known that I, PHILIP N. BRAUN, a citizen of the United States, and a resident of Syracuse, in the county of Onondaga and State of New York, have invented a certain new and useful Power Garment and Laundry Pressing Machine, of which the following is a specification.

This invention relates to garment and laundry power pressing machines, and has for its object particularly simple, efficient and durable means for automatically connecting and disconnecting the movable pressing element of the machine to the power actuated driving member or shaft.

The invention consists in the novel features and in the combinations and constructions hereinafter set forth and claimed.

In describing this invention, reference is had to the accompanying drawings in which like characters designate corresponding parts in all the views.

Figure 1 is a side elevation of a machine embodying my invention.

Figures 2 and 3 are enlarged sectional views on the plane of line 2-3, Fig. 1.

The machine here illustrated comprises cooperating pressing elements, as an upper pressing head 1 and a lower buck 2, the former being movable toward and from the latter and the buck 2 being here shown as mounted upon a suitable standard 3 which in turn is mounted upon a table 4 supported on front and rear legs 5, 6, there preferably being one rear leg arranged centrally of the table, this leg having an upwardly extending standard 7. The movable pressing element or head 1 is carried by a frame lever 8 pivoted at 9 between its end to the upper end of the standard 7 and is provided with a counterweight 10 at its rear end.

The upper pressing element or head 1 is secured to the forward arms of the frame lever 8 in any well known manner, and the forward end of the lever 8 is provided with a suitable handle 11 by means of which the press head may be pulled part way down toward the lower buck 2.

This invention comprises generally, a rotating driving member, motion transmitting means connected to the movable element or upper press head 1, a driven member connected to the motion transmitting

means, one of said members being shiftable into and out of connection with the other and being normally out of connection therewith, means controlled by the part way closing movement of the movable press element, and the motion transmitting means to shift the shiftable member into engagement with the other member, and means arranged to come into action after the press has been closed by the coaction of the driving and driven members to shift the shiftable member out of connection with the other member, against the action of the means tending to shift such shiftable member, the machine usually being provided with automatic latching means which holds the press closed, which pressing means is tripped preferably by operated tripping means as a trip lever.

In the illustrated embodiment of my invention, the driven member of the connector is shiftable into and out of engagement with the driving member and is carried by one of the motion transmitting parts which is movable adjacent the driving member during the part way closing movement of the press head 1.

The driving member is here shown as a cam 12 mounted on a shaft 13 suitably supported in the lower part of the frame, the shaft being connected through suitable gearing located in the casing 15 which gearing is connected through a shaft 16 to the armature shaft of an electric motor 17. The motor is mounted on the frame bar 14 and the casing is suspended from the bracket 18 depending from an upwardly diagonally extending brace or bar 19.

The motion transmitting means is here shown as toggle links 20 and 21, the link 20 being pivoted at 22 to the rear arm of the lever 8, the link 21 being pivoted at 23 to the lower end of the rear leg 6, the toggle links being pivoted together at 24. The toggle link 21 has a forwardly extending part or lever 25. The link 20 is composed of sections arranged to slide end-wisely relatively to each other against the resistance of a spring 26. Also, the usual coil spring 27 acts to pull upwardly on the lever or part 25. When the links of the toggle move toward a straight line upon depression of the lever 25 the press closes

and upon unfolding of the toggle lever the press opens, this action being well understood. As the construction of the toggle forms no part of this invention, further 5 description is thought to be unnecessary.

During the opening and closing of the press, the lever 25 moves in a vertical plane across the face of the cam 12.

The driven connector member is here 10 shown as a lever 28 mounted to rock on the shaft 29 supported by the part or lever 25, the connector carrying a cam follower or roller 30 for engaging the periphery of the cam 12. When the press is open, that is, 15 when the head 1 is up, the lever or part 25 is also elevated so that the cam follower 30 is out of position or out of line in an axial direction of the cam, that is, it is opposite the end face of the cam. Now, upon 20 part way closing movement of the head 1 by pulling down on the handle 11, the lever or part 25 also moves vertically carrying the connector 28 and follower 30 downwardly therewith into such position that the 25 follower may move laterally under the low point of the cam into engagement with the periphery of the cam.

The means for automatically moving the connector to carry the follower into engagement with the cam at the end of such 30 part way closing movement as here shown comprises a laterally extending horizontal arm 31 provided with a suitable weight 32 heavy enough to move the connector on its 35 pivot or shaft 29, this pivotal movement being limited by an annular flange 33 on the cam which the end of the roller abuts.

The cam 12 is constantly rotating and hence, when the cam follower 30 has been 40 moved into engagement with the cam 12 at the end of such part way closing movement of the press by the handle 11, the cam 12 which is rotating depresses the cam follower 30 and the lever 25 and hence 45 brings down the press head with pressure on the garment or other work on the lower buck 2.

This machine is provided with latching means for holding the press closed, such 50 means being here shown as a latch 34 pivoted at 35 to the inclined brace 19 and having its lower or latching end 36 movable into engagement with suitable means at the front end of the lever 25, the latch 55 34 being arranged to be swung by gravity into operative position, and being also provided with a light spring 37 tending to move it into latching position, this spring being interposed between an outwardly extending arm 38 at the upper end of the 60 latch and the brace 19.

The means at the front end of the lever 25 engaged by the latch 34 is here shown as a rocking lever 39 pivoted at 40 to the 65 front end of the lever part 25. The latch

engages the upper side of this lever above the pivot 40, these two parts being formed with rounding engaging surfaces.

The latch is tripped by a trip lever here shown as a pedal 41 pivoted at 42 to the frame and having an arm 44 arranged to engage an arm of the lever 39 to move the lever 39 upwardly on its pivot, and cause a shoulder or horn 45 on the upper side thereof to engage the latch and push 75 it out of latching engagement.

This latching mechanism forms no part of my invention, but is the invention of Albert Clisson of the town of Geddes, and State of New York. 80

The means for throwing the driven member or connector 28 out of engagement with the cam after the latch 34 has engaged the part or lever 25, that is, after the press has been closed, includes means arranged to come into action after the part 25 has been depressed to close the press head 1. As here shown, this means is a coiled spring 46 arranged in the path of the weighted arm 31 of the connector 28 and arranged to be engaged by such arm after the cam follower or roller 30 has engaged the periphery of the cam and to be compressed during the depressing movement of the cam 12 through the follower 30, the connector 28 and lever 25, so that when the latch engages and the toe of the cam 12 has left its position, the spring 46 reacts and throws the weighted arm upwardly, and hence rocks the connector 28 outwardly carrying the roller or follower 30 into the position shown in Fig. 3. 90

The bite or friction of the cam 12 on the roller 30 holds the roller engaged with the cam during the tensioning of the spring 46, and when the latch 34 engages the arm 25 and hence holds the press closed, there is a space between the periphery of the roller 30 and the low point of the cam so that the spring 46 is free to act against the weighted arm 31 and is not restrained by the friction of the cam 12 on the cam roller 30. In other words, during the rotation of the cam there is a space between the low point of the cam and the follower which permits the follower to move out of engagement with the cam. 100

The spring 46 is here shown as supported on the laterally extending foot 47 of a bracket 48 depending from the frame member 14. 110

In order to prevent engaging of the end face of the roller on the end face of the cam 12 when the presshead is open, and during the initial part of a part way closing movement, means is provided for holding the connector 28 in its "out" position when the press is open and the lever 25 is in its starting position. The means here illustrated comprises a weighted arm 50 120

loosely pivoted on the axis of the toggle lever 21 and arranged in the path of a laterally extending arm 51 at the upper end of the connector so that when the lever 5 is in its upper or starting position, this weighted arm 50 lies on or engages the arm 51 and prevents the connector 28 from being moved inwardly by its weighted arm 31 and during the initial part of the part 10 way closing movement of the pressing head 1, the lever 50 moves on its pivot and follows the arm 51 during the part way closing movement of the press, such following movement being limited by a stop arm 52 15 on the lever 50 engaging the stop surface at 53 on the frame.

In order to hold the connector out of engagement with the cam while the latch 34 is in latched position, that is, while the 20 press is closed, means is provided for holding the connector in its "out" position or the position to which it is thrown by the impulse of the throw out spring 46, as this spring 46 only extends far enough to throw 25 the connector out but not far enough to hold it away from the end face of the cam.

This means as here shown comprises a lock lever 54 preferably pivoted to the connector 28, it being here shown as pivoted between its ends at 55 thereto, the outer end of this lever 54 being heavier than the inner end so that the lever normally lies in the position shown in Fig. 2, the lever 30 being arranged so that when it is moved into straight position one arm thereof is interposed between the operator 25 and the side face of the lever 28. When in this 40 position, the movement of the lever 54 is limited by a shoulder 54^a on the connector 28.

The lever 54 is moved on its pivot against the action of its weighted arm by a suitable connection here shown as a spring 56 connected at its upper end at 57 to the weighted arm 50 and its lower end to the outer or heavier arm of the lever 54. A cord or wire may be used instead of this spring but preferably, in order to avoid the petty adjustments of a cord or wire as to the length thereof, a spring is used, this spring coming under sufficient tension to shift the lever 54 from its position shown in Fig. 2 to that shown in Fig. 3 when the part or lever 25 55 is depressed to its full extent by the cam 12.

Operation.

When the press is open the connector 28 is 60 in its out position, that is, in its position occupied when the roller 30 is out from under the cam or is opposite the end face of the cam, and it is held in this out position by the weight of the arm 50. When the press head 1 is closed by pulling down on the handle 11 the lever 25 also moves down-

wardly into the position shown in Fig. 2, and also the connector 28 moves downwardly therewith, as it is pivoted on the shaft 29 carried by the lever 25. During the initial part of the downward movement of the lever 25 and the connector 28, the weighted arm 50 follows the connector 28 or the arm 51 thereon and holds the connector 28 from being moved on its pivot 29 by the weighted arm 31 to carry the roller 30 toward the cam, until the movement of the arm 50 so holding the connector from pivotal movement is stopped by the engagement of its lever arm 52 with the stop surface 53, Fig. 1. This stop action takes place when the roller is 75 nearly in position to pass under the low surface of the cam 12.

A slight additional downward movement of the lever 25 and consequently a slight additional downward movement of the connector 28 frees the connector from the holding action of the weighted arm 50, so that, the connector is moved to the right on its pivot to the position shown in Fig. 2, wherein the roller is under the low point of the cam, such rocking movement of the connector 28 being affected by its weighted arm 31. The cam 12, which is constantly rotating, then depresses the roller 30, connector 28 and lever 25 into the position shown in dotted lines, Fig. 3, thus bringing the weighted arm 31 of the connector 28 onto the compression spring 46, and thereby compressing such spring. During such depression of the arm 25 by the cam 12 the latch 34, Fig. 1, comes into action and holds the lever 25 down and the press closed under pressure. Upon the first revolution of the cam 12 bringing the low point of the cam again opposite the roller 30, the spring 46 is free to react upwardly on the weighted arm 31 of the connector 28, and throws or flips the connector 28 on its pivot to the left into the position shown in Fig. 3, it being understood that the spring 46 is held from reacting while the high point of the cam is engaged with the roller 30, by the friction between the cam and the roller and that the low point of the cam is slightly separated from the roller when the arm 25 is held by the latch 34 in its depressed position.

During the downward movement of the lever 25 and connector 28, by the cam 12, the lock lever 54 is in its position, shown in Fig. 2, and as the weighted arm 50 is now held stationary owing to the engagement of its arm 52 with a stop shoulder 53, the movement of the connector 28 downwardly is relative to such weighted arm 50, and hence, such downward relative movement tightens the spring 56 as it is connected at one end to such weighted arm 50 and at its other end to the lock lever 54, carried by such connector and movable downwardly therewith.

Pivotal movement of the locking lever 54

by the spring is however prevented owing to the engagement of the locking lever with the lever 25, as shown in Fig. 2. However, as soon as the connector 28 is flipped outwardly by the spring 46 the spring 56 which has been previously tensioned, as explained, is free to react to move the locking lever 54 into its active position as shown in Fig. 3, where it holds the connector 28 from pivotal movement to the right by the weighted arm 31.

Hence, the connector 28, is held by the lock arm 54 from moving to the right and again carrying the roller under the cam 12 while the press is closed and under pressure.

Upon tripping of the latch 34, Fig. 1, the lever 25 is pulled upwardly by the spring 27 and the press opened principally by this spring 27 and counter weight 10.

As the lever 25 moves upwardly it causes the connector 28 and the locking lever 54 to move upwardly therewith, thereby releasing the tension in the spring 56 and as the lever 25 and the connector 28 approaches its uppermost position the connector 28 again engages and lifts the weighted arm 30 and the weight of this arm moves the connector 28 farther to the right and overbalances the weight of the arm 31 which arm 31 would now move the connector to the right.

Such slight additional movement of the lever 25 and the connector 28 releases the frictional engagement between the lock arm 54 and the lever 25, so that, the lock lever 54 is free to move into its position shown in Fig. 2, by its outer weighted end, and all parts are in their starting positions.

This machine is particularly advantageous in that the driving and driven elements, that is, the cam and the cam follower are thrown into and out of connection with each other without any attention on the part of the operator except the pulling down part way of the pressing head 1. This part way down movement of the pressing head 1 is primarily a safety-first proposition in order that the operator may close the press far enough to prevent the insertion of a hand between the pressing element before the power is applied, so that the cumbersome cages and other guarding means are unnecessary.

What I claim is:

1. In a pressing machine, a pair of cooperating pressing elements, one of which is movable toward and from the other and manually movable part way toward the other, a constantly moving driving member, motion transmitting means connected to the movable element, a driven member for coacting with the constantly moving driving member, one of said members being shiftable into and out of connection with the other and being normally out of connection

therewith and means controlled by the part way closing movement of the movable element for shifting the shiftable member into engagement with the other member while the driving member is in motion.

2. In a pressing machine, a pair of cooperating pressing elements, one being movable toward and from the other, and manually movable part way toward the other, a driving member, motion transmitting means connected to the movable element, a driven member for coacting with the driving member, one of said members being shiftable into and out of connection with the other and being normally out of connection therewith, and means controlled by the part way closing movement of the movable element for shifting the shiftable member into engagement with the other member, a latch arranged to hold the pressing element in pressing position, and means for shifting the shiftable member out of engagement with the other member when the latch is in holding position, substantially as and for the purpose specified.

3. In a pressing machine, a pair of cooperating pressing elements one movable toward and from the other and being manually movable part way toward the other, a rotating driving member, motion transmitting means connected to the movable element, and a connector shiftable into and out of connection with the driving member and being normally out of connection therewith, and means controlled by the manual part way closing movement of the movable pressing element to shift the connector into engagement with the driving member, substantially as and for the purpose set forth.

4. In a pressing machine, a pair of cooperating pressing elements one movable toward and from the other and being manually movable part way toward the other, a rotating driving member, motion transmitting means connected to the movable element, and a connector shiftable into and out of connection with the driving member and being normally out of connection therewith, and means controlled by the manual part-way closing movement of the movable pressing element to shift the connector into engagement with the driving member, latching means arranged to hold the movable pressing element in closed position, and means for shifting the connector out of engagement with the driving member when the latching means is in its holding position, substantially as and for the purpose described.

5. In a pressing machine, a pair of cooperating pressing elements, one movable toward and from the other and manually movable part way toward the other, a rotating driving member, motion transmitting means connected to the movable element in-

- cluding the part movable with the movable element during the part way closing movement thereof, and a connector carried by said part and shiftable by such part way 5 movement into position to be shifted into engagement with the driving member, and means for automatically shifting the connector into operative engagement with the driving member at the end of the part way movement, substantially as and for the purpose specified.
6. In a pressing machine, a pair of cooperating pressing elements one movable toward and from the other and manually 15 movable part way toward the other, a rotating driving member, motion transmitting means connected to the movable element including the part movable with the movable elements during the part way closing movement thereof, and a connector carried by said part and shiftable by such part way movement into position to be shifted into engagement with the driving member, and means for automatically shifting the connector into operative engagement with the driving member at the end of the part way movement, automatic latching means for holding the movable pressing element in pressing position, and means for shifting the connector out of engagement with the driving member when the latching means moves into operative position, substantially as and for the purpose set forth.
7. In a pressing machine, a pair of cooperating pressing elements one movable toward and from the other, and manual movable part way toward the other, a driving member, motion transmitting means connected to the movable element comprising a part 25 movable crosswise of the axis of the driving member, a shiftable connector carried by said part and shiftable into position to engage the driving member during the movement of said part by the part way closing movement of pressing element, and means for automatically moving such connector into engagement with the driving member, at the end of the part way movement, substantially as and for the purpose described.
8. In a pressing machine, a pair of cooperating pressing elements one movable toward and from the other, and manual movable part way toward the other, a driving member, motion transmitting means 30 connected to the movable element comprising a part movable crosswise of the axis of the driving member, a shiftable connector carried by said part and shiftable into position to engage the driving member during the movement of the lever by the part way closing movement of the pressing element, means for automatically moving such connector into engagement with the driving member, and means for automatically moving the connector out of engagement with
- the driving member when said part has been actuated by the driving member, substantially as and for the purpose specified.
9. In a pressing machine, a pair of cooperating pressing elements one movable toward and from the other, and manually movable part way toward the other, a driving member, motion transmitting means connected to the movable element comprising a part movable crosswise of the axis 75 of the driving member, a shiftable connector carried by said part and shiftable into position to engage the driving member during the movement of said part by the part way closing movement of pressing element, a latch coacting with said part to hold it in its operated position, and means for shifting the connector out of engagement with the driving member when the latch is in holding position, substantially as and for the purpose set forth.
10. In a pressing machine, a pair of pressing elements, one movable toward and from the other, and manually movable part way toward the other, a driving member, motion 90 transmitting means connected to the movable element comprising a part movable adjacent the driving member, a shiftable connector carried by said part and shiftable into position to engage the driving member during the movements of said member by the part way closing movement of the element, means for automatically moving the connector into engagement with the driving member, at the end of the part way movement, and means arranged to come into action after said part is actuated by the driving member to move the connector out of engagement with the driving member, substantially as and for the purpose described.
11. In a pressing machine, a pair of pressing elements, one movable toward and from the other, and manually movable part way toward the other, a driving member, motion transmitting means connected to the movable element comprising a part movable adjacent the driving member, a shiftable connector carried by said part and shiftable into position to engage the driving member during the movement of said part way closing movement of the element, an arm arranged to move the connector into engagement with the driving member, and means arranged in the path of the arm to engage said arm, and move the connector out of engagement with the driving member when the connector and said part have been actuated by the driving member, substantially as and for the purpose specified.
12. In a pressing machine, a pair of pressing elements, one movable toward and from the other, and manually movable part way toward the other, a driving member, motion transmitting means connected to the movable element comprising a part movable ad-

jacent the driving member, a shiftable connector carried by said part and shiftable into position to engage the driving member during the movements of said member by 5 the part way closing movement of the element, an arm associated with the connector and acting to move it into connection with the driving member, and yielding means arranged in the path of movement of such arm 10 during the movement of the connector and said part by the driving member, substantially as and for the purpose set forth.

13. In a pressing machine, a pair of pressing elements, one movable toward and from 15 the other, and manually movable part way toward the other, a driving member, motion transmitting means connected to the movable element comprising a part movable adjacent the driving member, a shiftable connector carried by said part and shiftable into position to engage the driving member during the movement of the element, an arm associated with the connector and operating to move the connector into engagement with the driving member, and a spring spaced apart from said arm and arranged in the path thereof to engage such arm during the movement of the connector and said part by the driving member whereby the spring 20 is tensioned during such movement of the connector and said part and shifts the connector out of engagement with the driving member, substantially as and for the purpose described.

14. In a pressing machine, a pair of pressing elements, movable toward and from the other, and manually movable part way toward the other, a driving element, motion transmitting means connected to the movable 40 element comprising a part movable adjacent the driving member, a shiftable connector carried by said part and shiftable into position to engage the driving member during movement of said member by the 45 part way closing movement of the element, means for automatically moving the connector into engagement with the driving member at the end of the part way movement, means arranged to come into action 50 when said part is being actuated by the driving member to move the connector out of engagement with the driving member, a latch for holding said movable element in its operative position, and means for tripping 55 the latch, substantially as and for the purpose specified.

15. In a pressing machine, a pair of pressing elements, one movable toward and from the other, and manually movable part way 60 toward the other, a driving member, motion transmitting means connected to the movable element comprising a part movable adjacent the driving member, a shiftable connector carried by said part and shiftable 65 into position to engage the driving mem-

ber during the movement of the element, a weighted arm associated with the connector and operating to move the connector into engagement with the driving member, and a spring spaced apart from said arm and arranged in the path thereof to engage such arm during the movement of the connector and said part by the driving member whereby the spring is tensioned during such movement of the connector, and said part, 70 and shifts the connector out of engagement with the driving member, a latch for holding said movable element in its closed position, and means for tripping the latch, substantially as and for the purpose set forth. 75

16. In a pressing machine, a pair of co-operating pressing elements, one movable toward and from the other, and manually movable part way toward the other, a driving member having a cam, a part 80 movable adjacent the driving member, a pivoted connector carried by said part and having a cam follower movable into and out of engagement with the cam and movable into position to be shifted to engage the cam by the part way movement of said part by the movable pressing element, means tending to rock the connector on its pivot in one direction to carry the follower into engagement with the cam, and means arranged to 85 come into action after the connector and said part have been actuated by said cam to move the connector on its pivot in the opposite direction against the action of the means tending to throw the connector into 90 engagement with the cam, substantially as and for the purpose described. 95

17. In a pressing machine, a pair of co-operating pressing elements, one movable toward and from the other, a driving member, motion transmitting means connected to the movable element including a member movable adjacent the driving member, a shiftable connector carried by said part and movable thereby during the part way movement of the pressing element into position to be shifted to engage the driving member, means tending to move the connector into engagement with the driving member, and means for holding the connector from movement by the former means when said part is in its starting position, substantially as and for the purpose specified. 100

18. In a pressing machine, a pair of co-operating pressing elements, one movable toward and from the other, a driving member, motion transmitting means connected to the movable element including a part movable adjacent the driving member, a shiftable connector carried by said part and movable 110 thereby during the part way movement of the pressing element into position to be shifted to engage the driving member, means tending to move the connector into engagement with the driving member, means for 115 holding the connector from movement by the former means when said part is in its starting position, substantially as and for the purpose specified. 120

19. In a pressing machine, a pair of co-operating pressing elements, one movable toward and from the other, a driving member, motion transmitting means connected to the movable element including a part movable adjacent the driving member, a shiftable connector carried by said part and movable 125 thereby during the part way movement of the pressing element into position to be shifted to engage the driving member, means tending to move the connector into engagement with the driving member, means for 130

- holding the connector from movement by the former means when said part is in its starting position, means arranged to come into action after the actuation of the connector and said part by the driving member to throw the connector out of engagement with the driving member, a latch for holding said part in its operative position, and means operated by the movement of said part by the driving member to hold the connector in its "out" position, substantially as and for the purpose set forth. 55
19. In a pressing machine, a pair of pressing elements one movable toward and from the other, and manually movable part way toward the other, a driving member, motion transmitting means connected to the movable element comprising a part movable crosswise of the axis of the driving member, the driving member having a cam thereon, a shiftable connector carried to said part and having a cam follower for engaging the cam and movable by the part way movement into position to shift into engagement with the cam, means tending to move the connector into engagement with the cam, means for holding the connector from movement by the former means when said part is in the starting position, movable means arranged to come into action after said part has been actuated by the cam to throw the connector out of engagement with the cam, a lock 60 carried by the connector and movable between the connector and said member for holding the part out of engagement with the cam when said part is in its operated position, and controlled by the movement of said part and said connector, automatic latching means for holding said part in its operative position, and means for tripping the latch, substantially as and for the purpose specified. 70
20. In a pressing machine, a pair of pressing elements, one movable toward and from the other, and manually movable part way toward the other, a driving member, motion transmitting means connected to the movable element comprising a part movable crosswise of the axis of the driving member, the driving member having a cam thereon, a shiftable connector operated to said part and having a cam follower for engaging 75 the cam and movable by the part way movement into position to be shifted to engage the cam, means tending to move the connector into engagement with the cam, means for holding the connector from movement 80 by the former means when said part is in the starting position, movable means arranged to come into action after said part has been actuated by the cam to throw the connector out of engagement with the cam, 85 a lock lever pivoted to the connector and having one arm arranged to move between the connector and said part when the connector is thrown "out", means acting on said lock lever and operated by the movement of said part, and means tending to move the lock lever to its inoperative position when the last mentioned means is inoperative, automatic latching means for holding said part in its operative position, 90 and means for tripping the latch, substantially as and for the purpose set forth. 95
21. In a pressing machine, a pair of pressing elements, one movable toward and from the other, and manually movable part way toward the other, a driving member, motion transmitting means connected to the movable element comprising a part movable crosswise of the axis of the driving member, the driving member having a cam thereon, a shiftable connector operated to said part and having a cam follower for engaging 100 the cam and movable by the part way movement into position to be shifted to engage the cam, means tending to move the connector into engagement with the cam, means for holding the connector from movement 105 by the former means when said part is in the starting position, movable means arranged to come into action after said part has been actuated by the cam to throw the connector out of engagement with the cam, a lock lever pivoted to the connector and having one arm arranged to move between the connector and said part when the connector is thrown "out", means acting on said lock lever and operated by the movement of said part, and means tending to move the lock lever to its inoperative position when the last mentioned means is inoperative, automatic latching means for holding said part in its operative position, and means for tripping the latch, substantially as and for the purpose set forth. 110
22. In testimony whereof, I have hereunto signed my name, at Syracuse, in the county of Onondaga and State of New York, this 20th day of February, 1923. 115

PHILIP N. BRAUN.
